UNITED STATES PATENT OFFICE.

SETH A. CRONE, OF EAST ORANGE, NEW JERSEY, ASSIGNOR TO BUFFALO BRAKE BEAM COMPANY, OF NEW YORK, N. Y., A CORPORATION OF NEW YORK.

RAILWAY BRAKE BEAM.

Application filed September 25, 1925. Serial No. 58,610.

The present invention relates to railway brake-beams and particularly to safety means applied to the spring plank or other portion of a car-truck for catching and supporting the brake-beams, should they, for any reason, become unhung and fall down.

An object of the present invention is to provide an inexpensive safety emergency support for brake-beams on car-trucks and the like which is in position at all times to engage immediately any part of the brake-beam mechanism accidentally broken or dislocated, to support same until the breakage is repaired, and to adapt such a support to be readily attached to the spring plank of the truck without danger of any parts being loosened and lost.

Another object of the invention is to adapt such a safety device to be supported from the spring plank of the car-truck by means of a U-shaped metallic strap having its upper ends flanged inwardly to be sprung about the plank or other portion of the truck to engage same rigidly.

Other and further objects of the invention will be obvious upon an understanding of the illustrated embodiment about to be described or will be obvious from the accompanying drawings or indicated in the appended claims, and various advantages secured by the invention other than those herein specifically referred to will occur to one skilled in the art, or become evident upon the employment of the invention in practice.

The invention about to be described is of particular utility in connection with trussed brake-beams hung transversely of a car-truck on opposite sides of the spring plank substantially parallel thereto, and contemplates the attachment of a supporting bracket at each end of the spring plank, by means of metallic straps extending within the brackets and upwardly therefrom whereby their free ends may be sprung into rigid and secure engagement with said plank to hold the brackets in position. Suitable safety supporting members fit firmly in said brackets and extend outwardly slightly below and beyond the brake-beams on the respective sides of the plank whereby, if the beams should drop from their customary position, each of them would be caught by the outer ends of the extended members and supported at two points to prevent their

falling beneath the wheels of the truck. Wedge pins are inserted through apertures in the brackets to engage and lock the safety members in position.

A preferred embodiment of the invention has been selected for purposes of illustration and description, and is shown in the accompanying drawings wherein,

Fig. 1 is a top plan view of a portion of a car-truck illustrating the present invention applied to the spring plank and the relation of the brake-beams thereto;

Fig. 2 is a cross-sectional view taken along the line 2—2 of Fig. 1;

Fig. 3 is a cross-sectional view along the line 3—3 of Fig. 1, showing in detail the safety bars rigidly secured in a bracket attached to the spring plank by means of a strap sprung into position thereon;

Fig. 4 is a cross-sectional view along the line 4—4 of Fig. 2 illustrating details of the invention;

Fig. 5 is a cross-sectional view along the line 5—5 of Fig. 2 illustrating in detail the application of the locking pin for securing the safety bars in position;

Fig. 6 is a modified form of my invention illustrating another way of securing the safety bars in the supporting brackets;

Fig. 7 is a cross-sectional view along the line 7—7 of Fig. 6 illustrating details of the modified form of the invention;

Fig. 8 is a cross-sectional view along the line 8—8 of Fig. 6;

Figs. 9 and 10 illustrate the application of a specific type of punch for forming apertures with bearing surfaces in the sides of the channel supporting brackets or in the sides of the safety bars as the case may be;

Fig. 11 is a detailed perspective view of the end of a safety bar showing the corners thereof bent outwardly to prevent its removal from the supporting bracket; and

Fig. 12 is a view similar to that shown in Fig. 11 illustrating another way of forming projections on the ends of the safety bars.

Referring more particularly to the drawings, there is shown a spring plank 15 of the well known channel form, with the usual type of inside hung trussed brake-beams 16 on the respective sides thereof comprising a compression member 17, a tension member 18, and a strut 19 extending transversely of the central portions of the members and adapted to be attached to brake-applying 110

devices not shown. It will be understood that at the juncture of the respective ends of the tension and compression members of the brake-beams, brake-shoes are attached 5 for engagement with the four wheels of the truck when pressure is applied to move the brake-beams away from the spring plank. A more detailed explanation of the relation of the spring plank and brake-beams to the 10 parts of a car-truck may be found in the patent to Henry C. Williamson, No. 567,428, dated September 8, 1896.

To prevent the parts of the brake-beam from falling in cases of loosened bolts, 15 broken parts and the like, there is provided a safety supporting bar 20 at each end of the spring plank to extend transversely thereof and outwardly below and beyond the ends of the brake-beams to prevent their 20 dropping beneath the trucks. Each safety bar is secured to the spring plank by means of a channel supporting bracket 21 having a flat upper portion 22 and downwardly depending parallel side portions 24 properly spaced to receive the safety bar 20.

A U-shaped strap 25 extends through the channel of the bracket 21 with its bottom portion 26 enveloped by the sides 24 and riveted to the upper portion 22 of the bracket 30 by means of rivets 27 countersunk in the latter. The upper ends of the strap 25 are flanged inwardly at 28 and the entire strap has dimensions slightly greater than the cross-sectional dimensions of the spring 35 plank 15 so that it may be sprung into position thereabout, as shown in Figs. 2 and 3, with the flange 28 thereof engaging the upper edges of the sides of the plank and with the flat upper portion 22 of the bracket 21 held firmly against the bottom of the plank. 40 The parts are further secured in position and prevented from moving longitudinally of the plank by means of the rivets 29 extending through the sides of the plank and the upwardly extending portions of the strap. Rivets are used for the attachment 45 of the various parts together in preference to bolts and the like for the reason that they are more positive in operation and less likely 50 to corrode excessively.

The depending parallel sides 24 of the bracket 21 are flanged inwardly and upwardly at their lower edges as shown at 30 to provide a pair of guideways 31 extending longitudinally of the bracket. The safety bars 20 are preferably of inverted channel-shaped cross-section with a longitudinal groove or recess 34 to add strength to the bar without increasing its dimensions. In 60 use the sides of the channels extend downwardly and fit into the guideways 31 whereby the bar may slide along same until it is in proper position. The center of the bar is depressed on its upper side, as shown at 33 65 in Figs. 3 and 5, so that it may be properly

positioned and locked in place. Suitable apertures 35 are formed in the sides 24 of the bracket to receive a pin 36, having a head 37 at one end and a tapered forward end 38 to enter the depression at the center of the safety bar and exert a wedge-like action to press the bar downwardly, and lock it firmly in position. The upper portions of the apertures 35 have inturned flanges 40 which act as bearing surfaces for the pin 36 75 to facilitate its movement over the safety bar.

The apertures 35 and proper bearing surfaces therefor may be conveniently formed by means of a punch 41, shown in Figs. 9 80 and 10, which has a lower cutting surface 42 and an upper surface 44 set back therefrom to press the metal at the upper part of an aperture inwardly to form the bearing flange 40.

A suitable cotter pin may be secured in an aperture 45 at the end of the pin 36 to hold it in position. As a further precaution against loss of the pin 36, a U-shaped locking member 46 formed of sheet metal adapted to fit about the lower portion of the bracket 21 and having apertures to correspond with the apertures 35 in the bracket, may be placed in position so that the bolt 36 will pass through the apertures in its respective ends. The elongated leg 47 of the U-shaped member is bent downwardly over the head of the pin 36 when in position to prevent removal in case the cotter pin is lost. This form of lock is shown in several of 100 my copending applications, and no claim to it is made herein.

A modified form of the invention is shown in Figs. 6, 7 and 8 wherein the inverted supporting bracket 21 is secured by means of the strap 25 to the spring plank as described hereinbefore; but the safety bar is formed without a depression at its center or a groove extending longitudinally at the top thereof, it being adapted to fit flat against the strap 110 25 which extends through the upper portion of the inverted bracket. The depending sides 24 of the bracket are bent inwardly at their respective ends only, thereby forming supporting shelves 50 to receive the lower 115 edges of the safety bars. Suitable apertures 51 are formed in the sides 24 of the bracket, the supporting surfaces for the pin 36 being formed at the center of the safety bar by portions on the lower edge thereof being bent 120 inwardly at 54 to form a recess therein. The pin 36 extends through the apertures 51 and engages the supporting surfaces 54 to lock the safety bar firmly in position and to press it tightly against the strap 25 in the upper part of the supporting bracket 21. The locking means 46 and a suitable cotter pin 125 are provided, and mounted as described hereinbefore to prevent loss of the pin 36.

In Figs. 11 and 12, there is shown de- 130

tailed perspective views of the ends of safety bars, each of which has a lug formed at the corners of the sides thereof to prevent loss of the bar in case the pin 36 should be forgotten or lost, by engaging the side of the supporting bracket when the safety bar works to one side or the other of the car-truck. In Fig. 11, the corners of the depending sides are bent outwardly at 55 without mutation thereof. This form of lug is applicable with sheet metal which may be bent without serious effort. In Fig. 12, the sides of the bar are slotted for a short distance and the slotted portion is bent outwardly to 15 form locking lugs 56.

It will be seen that the present invention comprises a minimum of individual parts which may be readily and securely assembled, and applied to the spring plank of a 20 car-truck in a minimum time. The safety bars are adapted to engage a deranged brake-beam at two points and maintain it out of contact with the rails or the moving parts of the truck until repairs can be made. 25 All parts of the device are rugged in construction and securely and rigidly fixed to each other to withstand the rough usage which devices of this general character encounter. As various embodiments may be 30 made in the invention above described, it is to be understood that all matter herein set forth is to be interpreted as illustrative and not in a limiting sense.

Having thus described my invention, what 35 I claim is:—

1. In a car-truck having a spring plank and inside hung brake-beams, the combination of a supporting bracket at each end of the spring plank, said brackets having depending longitudinal sides with apertures formed therein, safety bars mounted in the sides of said brackets and extending longitudinally of the truck beneath the brake-beams, each of said safety bars having a depression adjacent the apertures in said bracket, pins extending through said apertures to engage said depressions and lock said safety bars in position, said apertures having bearing surfaces on the upper sides thereof in 45 opposition to the depressions of the safety bars to facilitate the insertion of the pins therein, and metallic straps for attaching said brackets to said spring plank each comprising a horizontal portion extending between the sides of the bracket, and upstanding end portions adapted to be sprung into engagement with the spring plank for supporting the brackets and the safety bars mounted therein.

2. In a car-truck having a spring plank and inside hung brake-beams, the combina-

tion of metallic supporting brackets secured to the spring plank and provided with means for supporting safety bars, each of said brackets having opposite apertures, safety 65 bars supported by the brackets, and pins extending through said apertures and engaging and holding the safety bars in position, said brackets having integral deflected parts extending in such directions as to furnish 70 the apertures with extended bearing surfaces for the pins in opposition to the safety bars.

3. In a car-truck having a spring plank and inside hung brake-beams, the combination of metallic supporting brackets secured to the spring plank and provided with means for supporting safety bars, each of said brackets having opposite apertures, and pins extending through said apertures and engaging the bars, said brackets having integral deflected parts extending in such direction as to furnish the apertures with extended bearing surfaces for the pins at their sides opposite to their engagement with the bars. 85

4. In a car-truck having a spring plank and inside hung brake-beams, the combination of a metallic supporting bracket secured to the spring plank and provided with means for supporting a safety bar, said bracket having oppositely disposed apertures, and a pin extending through said apertures for engagement with notched portions of the safety bar, said bracket having means adjacent each of said apertures to form extended bearing 90 surfaces for the pin in opposition to the notched portions of the safety bars. 95

5. A bracket for supporting safety bars and the like, comprising a pair of depending sides bent inwardly at the lower portions 100 thereof to form bar supporting means, and oppositely disposed apertures in the sides of said bracket adapted to receive a pin for engaging a safety bar to secure it in position, said sides having integral portions extending inwardly adjacent said apertures to form extended bearing surfaces for the safety bar securing pin in opposition to the safety bar. 105

6. In a car truck having a spring plank and inside hung brake-beams, the combination of metallic supporting brackets secured to the spring plank and provided with seats for supporting the lower side of safety bars, each of said brackets having alined apertures immediately above the top side of the 110 safety bars, and pins extending through said apertures to maintain the bars in position, said brackets having means extending inwardly to provide, at the apertures, bearing surfaces for the top sides of the pins. 115

SETH A. CRONE.
